(57) **CLAIM**

I claim the ornamental design for the shaving razor handle, as shown and described.

DESCRIPTION

FIG. 1 is a left front perspective view of a shaving razor handle having a blade cartridge attached;

FIG. 2 is a left front perspective view of the shaving razor handle of FIG. 1 without the blade cartridge attached; FIG. 3 is a right bottom perspective view of the shaving razor handle of FIG. 2;

FIG. 4 is a front elevational view of the shaving razor handle of FIG. 2;

FIG. 5 is a rear elevational view of the shaving razor handle of FIG. 2;

FIG. 6 is a top plan view of the shaving razor handle of FIG. 2;

FIG. 7 is a bottom plan view of the shaving razor handle of FIG. 2;

FIG. 8 is a left side elevational view of the shaving razor handle of FIG. 2;

FIG. 9 is a right side elevational view of the shaving razor handle of FIG. 2;

FIG. 10 is a left front perspective view of a second embodiment of a shaving razor handle having a blade cartridge attached;

FIG. 11 is a left front perspective view of the shaving razor handle of FIG. 10 without the blade cartridge attached;

FIG. 12 is a right bottom perspective view of the shaving razor handle of FIG. 11;

FIG. 13 is a front elevational view of the shaving razor handle of FIG. 11;

FIG. 14 is a rear elevational view of the shaving razor handle of FIG. 11;

FIG. 15 is a top plan view of the shaving razor handle of FIG. 11;

FIG. 16 is a bottom plan view of the shaving razor handle of FIG. 11;

FIG. 17 is a left side elevational view of the shaving razor handle of FIG. 11; and,

FIG. 18 is a right side elevational view of the shaving razor handle of FIG. 11.

The broken line blade cartridge illustrates the environment of the shaving razor handle. The remaining broken lines illustrate portions of the shaving razor handle and form no part of the claimed design.
